DESIGN FOR A BOX FOR PACKING AND EXHIBITING

Charles K. Ellsworth, Sandusky, Ohio, assignor to The Hinde and Dauch Paper Company,
Sandusky, Ohio, a corporation of Ohio

Application July 27, 1933. Serial No. 48,853

Term of patent 14 years

To all whom it may concern:

Be it known that I, CHARLES K. ELLSWORTH, a citizen of the United States, and a resident of Sandusky, county of Erie and State of Ohio, have invented a new, original, and ornamental Design for a Box for Packing and Exhibiting, of which the following is a specification, reference being had to the accompanying drawing, forming a part thereof.

In said annexed drawing:

The figure is a view of the article in perspective showing the design on one side and one end.

In the drawing the shading is not intended to represent any particular color.

I claim:

The ornamental design for a box for packing and exhibiting as shown and described.

Signed by me this 25th day of July, 1933.

CHARLES K. ELLSWORTH.
